UNITED STATES PATENT OFFICE.

GEORGE HENRY FOX, OF BOSTON, MASSACHUSETTS.

PISTON WATER-METER.

SPECIFICATION forming part of Letters Patent No. 327,672, dated October 6, 1885.

Application filed December 20, 1884. Serial No. 150,804. (No model.)

To all whom it may concern.

Be it known that I, GEORGE HENRY FOX, a citizen of the United States, residing at Boston, in the county of Suffolk and State of Massachusetts, have invented certain new and useful Improvements in Water-Meters; and I do hereby declare the following to be a full, clear, and exact description of the invention, such as will enable others skilled in the art to 5
10 which it appertains to make and use the same, reference being had to the accompanying drawings, and to letters or figures of reference marked thereon, which form a part of this specification.

15 This invention relates to "piston water-meters," so called, and belongs especially to that class in which two reciprocating pistons are employed, and so arranged that a dead-center is avoided and stoppage prevented.
20 My invention consists, essentially, in the employment in the pistons of independent reciprocating plungers, whereby variation in the capacity of water-space on either or both sides of the pistons is readily accomplished; and, 25 furthermore, in the construction of a mid rib or partition separating the two pistons, and which is provided with oppositely-disposed recesses to accommodate the crank-arms, and an easy and ready way is accomplished of dividing the cylinder into two separate watertight chambers, and isolated one from the other.

Hitherto in meters of this class two cylinders have generally been arranged side by side, 35 or else the cranks operating the pistons have worked in a common measuring-chamber; hence there has always been need of stuffing boxes and packing, while the number of parts has been increased with a large attendant expense. In my present device there are no stuffing-boxes, and the apparatus is made extremely compact and very much more cheaply than any of the above briefly-described devices.

45 In the drawings accompanying this specification, Figure 1 represents a central vertical longitudinal section of a meter embodying my improvements, while Fig. 2 is a plan of the valve-seats and their passages, and Fig. 3 a 50 plan of the eccentrics as shown in section in Fig. 1. Fig. 4 is a horizontal section on line $x-x$, (see Fig. 1,) with the crank removed.

In the above drawings I have shown the body of the meter at A, with a cap, B, containing the valves a a' , which are ordinary slide-valves, and operated by the eccentrics b b' , mounted upon a shaft, C, located centrally of the meter, and revolving within the bore c formed within the partition or mid-rib D, which separates the meter into two similar measuring-chambers, E F. This partition is cast with two oppositely-disposed recesses, G H, which afford an easy and ready expedient for completely isolating the two chambers from each other, and also affords space for the rotary movements of the cranks d e , to which are attached one end of the piston-rods f g , while their other extremities are secured to the pistons I J. In order to introduce the shaft C, with the cranks attached, I have made one 55 casting, G', forming the recess G, separate from the partition D, and secured by bolts to the latter. These two pistons with their valves and operating mechanism are disposed very similar to that of the same relative parts in a steam-engine—that is, the crank-pins and eccentrics are set quartering, to prevent a dead-center. The passage of fluid through this meter is as follows: The inlet-pipe K delivers the water directly through the port h into the valve-chamber K' formed by the cap B, whence it passes into both ends of each cylinder by and through the inlet-ports i i' j j' . Furthermore, these ports alternately become exhaust-passages and co-operate with the exhaust-ports k k' , which communicate by the passages h h' , leading to the outlet-pipe L, communicating with the building.

An essential and important part of my invention, however, I consider consists in a 85 plunger or plungers, M N, arranged to move in the piston-heads, which may be, if desired, provided with one or more of such plungers. These plungers perform a very important function in meters of this class above 90 premised, since water is non-elastic and decidedly different from steam; hence there is an entirely different set of forces and resultants to be considered in the employment of water as an element in lieu of steam in such an apparatus. Moreover, there is one obstacle in the working of a meter of this class consequent upon the non-elastic properties of water very difficult to overcome, which is 95 100

this: Upon reference to Fig. 1 I have shown as nearly as possible the condition of the parts when the trouble to be overcome has occurred. In this figure the piston J is at 5 half-stroke and piston I just completing its outward or advance stroke. Now, at this 10 particular moment the piston-rod f and crank d are in a position, just prior to their alignment on the center, at which time the valve a', moving in the direction of arrow 1, has closed the inlet and outlet ports and the fluid is 15 locked for a very small space of time within the measuring-chamber F. Now, the crank and piston must advance a trifle more to 20 reach their extreme throw—say the distance represented between the broken line 1 2 and the line of the piston—and are then actuated and driven by the opposite piston, J, under the full-supply pressure; but as water is non- 25 elastic, and a certain part of it is now confined between the head of the cylinder and piston by the momentary closing of the valve a', it follows that some of the operative parts must either yield or break, thus 30 destroying the apparatus and preventing its further employment until repaired, or else lift and force the valve a' from its seat. To 35 overcome this difficulty, I have employed a plunger consisting of a short cylinder, l, provided with heads m n, and have bored the piston so that the cylinder l snugly fits the hole in the piston-head, which is thickened at that point to furnish a bearing, while the heads m n prevent its displacement and compel it to reciprocate in its respective head. Thus it follows that as the piston advances this slight distance to the line 3 4, while the valve has closed both the outlet and inlet ports, it is necessary to employ some means 45 to increase the water-space in advance of the piston, or else remove some water to allow said piston free movement for its passage, while on the other hand the water-space at the rear of said piston requires to be diminished, or else there is a tendency to produce a vacuum.

The plunger M during the entire advance stroke just accomplished was in the opposite extreme of movement to that shown, with 50 the head m bearing against the piston under the influence of the supply-pressure through the port j, which is greater than that upon the outer exhaust side of said piston. This position is maintained until the valve a' has 55 closed all communication with the chamber F, when, as the piston advances slightly, the space occupied by the water on the hitherto exhaust side is diminished. Now, the water-space at this time must be increased, since 60 the water cannot escape, and consequently the plunger at once reciprocates to its opposite extreme, as now shown. By this movement the water-space in advance of the piston is increased by an amount equal to the cubic 65 contents displaced by the length of cylinder l, projecting into said water-space, and the pressure is at once relieved. On the other

hand, the slight advance of the piston has increased the water-space upon its rear side, and the tendency to a vacuum is at once obviated in the said water-space by the movement of the plunger rearward, and thus said space has been diminished by an amount equal to the cubic contents of the same cylinder, which has just been removed from the water-space upon the other or advance side, and a complete balance is maintained without any undue strains being brought to bear upon any of the operative parts of the meter. 75

The plunger now remains in this position 80 after the valve a' has moved sufficiently to admit supply-water between the piston and the head of the cylinder to compel it to advance on its retreat movement, and so continues until the valve again covers both inlet and outlet 85 ports preparatory to a change of position, in order to alter the movement of said piston.

It will not be necessary for me to enter into a detailed description of the complete operation of this apparatus, since reference to the 90 figures will readily convey to the mind the co-operation and relation of the various parts one to the other. I will simply say that in Fig. 1 the valve a' is advancing in the direction of arrow 1 to permit the measured fluid 95 in chamber F to exhaust by the passages j, k', and k² to the outlet-pipe L, while fresh liquid is permitted to enter through inlet-pipe K, passages h j', and thence between the piston I and the cylinder-head. On the other hand, the valve a is in such position that supply-liquid is flowing from the inlet-pipe K through ports h and i into the left-hand side of measuring-chamber E, and has driven the piston J one half of its stroke in the direction of arrow 105 2, and the recently-measured fluid is exhausting from the other portion of the chamber E by and through the passage i', leading to the ports k and passage k', to the outlet L. 110

The registering apparatus is to be connected 115 to the top of the shaft C by some simple mechanical means, and every revolution of the shaft is recorded; or, in other words, double the amount of liquid contained in each cylinder, or twice the cubic contents of the latter, 120 is thereby registered upon the dial.

It is evident that one or more of these plungers above described may be arranged in a single piston-head, and, furthermore, the diameter and length of the cylinder or compensating part thereof may be changed, and thus variation of the water-space on either or both sides of a piston is easily adjusted to any desired amount. 125

An apparatus similar to the one above described and embodying my invention is simple, cheaply made, and very effective in its operations, since the valves are positively actuated, and there is no chance for a dead-center; moreover, the apparatus, when the 130 valves are properly adjusted, is certain to operate, no matter how small a stream is passing through it, with no danger of stoppage upon a dead-center.

I claim—

1. A meter arranged as herein described, and divided into two measuring-chambers separated by a partition provided with hollow oppositely-disposed recesses, substantially as described, and for the purposes herein set forth.
2. The combination, with a piston and its cylinder, of a device operating to increase the water-space in front of the piston proportionally to the advance of said piston at the moment of closing the adjacent outlet and inlet ports, substantially as herein described.
3. The combination, with a piston and its cylinder, of a device operating to decrease the water-space in rear of the piston proportionally to the retreat of said piston at the moment of closing the adjacent outlet and inlet ports, substantially as and for purposes herein set forth.
4. The combination, with a piston and its

cylinder, of a device operating to increase or diminish the water-space upon either side of the piston at the moment of closing both the adjacent outlet and inlet ports, substantially as described.

5. The plunger, as a mechanical device for effecting the variations in the capacity of the water-space on either or both sides of the piston, and operating substantially for the purposes herein set forth.

6. The combination of a cylinder and its pistons with their operative mechanism and the compensating plungers, substantially as stated.

In testimony whereof I affix my signature in presence of two witnesses.

GEORGE HENRY FOX.
